UNITED STATES PATENT OFFICE

JAMES A. LAVIN, OF NEW YORK, N. Y.

DESIGN FOR A BULK MEASURING DEVICE

Application filed March 2, 1931. Serial No. 38,891. Term of patent 7 years.

To all whom it may concern:

Be it known that I, JAMES A. LAVIN, a citizen of the United States, residing at New York, in the county of New York and State of New York, have invented a new, original, and ornamental Design for Bulk Measuring Devices, of which the following is a specification, reference being had to the accompanying drawing, forming part thereof.

The figure is a perspective view of a measuring device, showing my new design.

I claim:

The ornamental design for a bulk measuring device, substantially as shown.

JAMES A. LAVIN.
